UNITED STATES PATENT OFFICE.

ROBERT E. KEMBER, OF NEW YORK, N. Y., ASSIGNOR TO E. E. LLOYD PAPER CO., OF CHICAGO, ILLINOIS, A CORPORATION OF ILLINOIS.

DESIGN FOR SAFETY PAPER.

Application filed January 29, 1929. Serial No. 29,830. Term of patent 14 years.

To all whom it may concern:

Be it known that I, ROBERT E. KEMBER, a subject of the King of Great Britain, residing at New York, in the county of New York and State of New York, have invented a new, original, and ornamental Design for Safety Paper, of which the following is a specification, reference being had to the accompanying drawing, forming part thereof.

The figure is a face view of a piece of safety paper showing my new design.

I claim:

The ornamental design for safety paper as shown.

R. E. KEMBER.
